CLAIM

The ornamental design for a display screen or portion thereof with game board GUI as shown and described.

DESCRIPTION

The single FIGURE is a front view of the display screen or portion thereof with game board GUI.

The dash-dot-dash border line shows a portion of the display screen of the display screen or portion thereof with game board GUI, is included for the purpose of illustrating portions of the article, and forms no part of the claimed design.

(Continued)

The dashed broken lines showing parts of the display screen or portion thereof with game board GUI are included for the purpose of illustrating portions of the article and form no part of the claimed design.
